UNITED STATES PATENT OFFICE.

PAUL J. STUPARICH, OF SAN FRANCISCO, CALIFORNIA.

PHOTOGRAPHIC CARD-MOUNT.

SPECIFICATION forming part of Letters Patent No. 687,411, dated November 26, 1901.

Application filed August 19, 1901. Serial No. 72,517. (No model.)

To all whom it may concern:

Be it known that I, PAUL J. STUPARICH, a citizen of the United States, residing in the city and county of San Francisco, State of California, have invented an Improvement 5 in Photographic Card-Mounts; and I hereby declare the following to be a full, clear, and exact description of the same.

My invention relates to a novel formation 10 of cards which may be employed as photographic mounts, and for other like or similar purposes.

It consists in forming the card with a pasteboard or similar base of considerable thickness 15 and applying to the front a thin veneer of wood, which is cemented to the cardboard so as to form substantially an integral part thereof. The surface thus formed may afterward be indented or raised by a die in any 20 suitable or desired form.

Referring to the accompanying drawings, A is the base of my improved card, which is made of paper or what is termed "pasteboard," having a considerable thickness and 25 consequent stiffness or rigidity to resist bending or distortion.

2 is a thin veneer, made of wood of any suitable or desired description, and this veneer is cemented and permanently attached to one 30 side of the pasteboard backing, thus forming a composite structure the face of which serves to receive photographic mounts or for

other required purposes. This face may be formed with a raised central portion, or it may be sunken so as to form a sort of outline 35 or border interior to the outer periphery and serving as an ornamental margin for the photograph which may be mounted thereon.

Having thus described my invention, what I claim as new, and desire to secure by Letters 40 Patent, is—

1. The combination in a photographic mount, of a flexible and impressible backing and a facing of correspondingly flexible and 45 impressible wooden veneer.

2. The combination in a photographic mount of a flexible material capable of permanent indentation and a facing of flexible and impressible wood veneer cemented to and forming a permanent part of the mount. 50

3. The combination in a photographic mount of a foundation or body of flexible and impressible material, a facing of thin flexible wood veneer adherent to and forming a permanent part of the body, said mount 55 having its surface afterward indented or sunken as described.

In witness whereof I have hereunto set my hand.

PAUL J. STUPARICH.
